UNITED STATES PATENT OFFICE.

JOHN C. RIETHMÜLLER, OF ALLEGHENY, PENNSYLVANIA.

IMPROVEMENT IN BALE-TIES.

Specification forming part of Letters Patent No. **172,936**, dated February 1, 1876; application filed November 30, 1875.

To all whom it may concern:

Be it known that I, JOHN C. RIETHMÜLLER, of Allegheny, in the county of Allegheny and State of Pennsylvania, have invented a new and useful Improvement in Cotton-Bale Tie; and I do hereby declare the following to be a full, clear, and exact description thereof, reference being had to the accompanying drawing, forming a part of this specification, in which—

Figure 1 is a view of the end of a bale-band and a tie embodying my invention. Fig. 2 is a transverse section of the ends of the bale-band and the tie.

Like letters refer to like parts wherever they occur.

My invention relates to that class of bale-ties in which the slotted ends of the bale-band are locked by a loose or detachable button; and it consists in combining with the button an open ring or detachable washer or similar device, by means of which the button may be securely, though movably, attached to one end of the bale-band, with which it is to be employed.

Heretofore in slotted bale-bands where a loose button has been employed it has been liable to become detached and lost, or to fly when the bale was suddenly loosened, to avoid which the button has been loosely riveted to the hoop, which rendered the fastening insecure, and liable to break or drag out, or firmly riveted, which rendered the tie nothing more than a hook, liable to become unlocked from the spring of the bale in handling. In the last two cases the buttons became scrap in common with the band, when the latter was cut in loosening the bale, and in the former case it was frequently lost.

The object of the present invention is to overcome these several objections to the use of the button, and to attach the button to the

bale, so that it can be removed from the cut band or scrap and reused.

I will now proceed to describe my invention, so that others may apply the same.

In the drawing, A is a bale-band, provided with the slots *a a*, of such form as will permit the passage of the cross-piece of the button employed. B is a button, having the usual neck *b* and a cross-piece, *b'*. A cross-piece is employed in preference to a right-angular bend or projection, for the reason that a washer is better retained by the cross-piece. *c* is a split washer, sufficiently large to fit loosely on neck *b* of the button, and to prevent the escape of the cross-piece *b'*. The bale-band is slotted, and the button and washer formed in the usual manner. The cross-piece of the button is passed through one of the slots of the band, the split washer placed around the neck of the button, and closed by a pair of pliers, completing the tie for shipment or use.

When the band has been cut in loosening the bale, or from other causes becomes useless as a bale-band, the locking device may be readily removed for use upon another band; or, if the locking-slot should tear open, the button may be secured in a second slot, which cannot be done with the riveted button.

Having thus described my invention, what I claim, and desire to secure by Letters Patent, is—

In combination with the slotted bale-band and detachable locking device, an open ring or detachable washer, for retaining the locking device, substantially as specified.

In testimony whereof I, the said JOHN C. RIETHMÜLLER, have hereunto set my hand.

JOHN C. RIETHMÜLLER.
